UNITED STATES PATENT OFFICE

2,008,051

DIRECTION SIGNAL

John Florian Waldman, Enid, Okla.

Application August 22, 1933, Serial No. 686,289

1 Claim. (Cl. 177—327)

This invention appertains to new and useful improvements in electrical signalling, and more particularly to a novel direction signal for use on motor vehicles.

5 The principal object of the present invention is to provide a direction signal of the semaphore type which can be readily operated by the driver without in any manner encumbering his action at the steering wheel.

10 Still another important object of the invention is to provide a signal for motor vehicles wherein the details are so constructed as to not be susceptible to the development of ready defects.

Other important objects and advantages of the 15 invention will become apparent to the reader of the following specification.

In the drawings:

Figure 1 represents a fragmentary vertical sectional view through an automobile body, showing 20 in rear elevation the signal semaphore and its control means.

Figure 2 represents a rear elevational view of the semaphore.

Figure 3 represents a top plan view of the semaphore with a part thereof broken away.

Figure 4 represents a side elevational view of the control.

Figure 5 represents a vertical sectional view through the control.

30 Figure 6 represents a sectional view taken substantially on line 6—6 of Figure 5.

Figure 7 represents a side elevational view of the contactor.

Figure 8 represents a perspective view of the contactor with the roller removed.

Referring to the drawings wherein like numerals designate like parts, it can be seen in Figure 1, that numeral 5 represents the body of an automobile, while numeral 6 generally refers to the 40 semaphore of the signal, while numeral 7 represents the control means whereby the semaphore is operated. The semaphore consists of an inwardly tapering lamp box 8 having front and rear panes 9—9. Located within this lamp box 8 is an incandescent bulb 10, while a pair of leg members 11—11 protrude from the inner end of the lamp box and are pivotally connected to the bracket 12 on the body 5 by a pin 13. A coiled spring 14 on the pin 13, having one end attached 45 to the bracket 12 while the other end is attached to one of the legs 11, serves as a means for automatically elevating the semaphore 6 when it is released by the control 7.

50 As can be clearly seen in Figures 4 to 8, inclusive, the control consists of a circular casing 15 having

a removable dial plate 16 in one side thereof. A shaft 17 is journaled through this dial plate 16 and terminates within an opening in the back wall of the casing 15, which opening registers with an opening 18 in the bracket clamp 19 which attaches the casing 15 to the steering shaft housing 20.

5 Numerals 21 represents a drum attached to the shaft 17, as at 22, and on this drum the cable 23 can be wound. This cable 23 extends downwardly 10 through an opening 24 in the bottom of the casing 15 and is trained under a pulley 25 and as many other pulleys as may be required to attach, as at 26, to the inner end portion of the semaphore 6.

This drum 21 is provided with an inwardly disposed circumferentially extending flange 27 which has a plate 28 of di-electric material secured thereto at its inner periphery. This plate 28 of di-electric material has a recess 29 therein, which is the inactive position of the semaphore. 20

This flange 27 is provided with a low semaphore 25 position notch 30, a horizontal position notch 31 and an elevated or high semaphore position notch 32. Obviously, whenever the semaphore is in operative position, the contact roller 36 is in engagement with the edge of the annulus 27, and when the semaphore signal is in retracted position, the roller 36 is engaged with the plate 28, which is of insulation.

A bracket 33 of current conductive material is 30 attached to the back side of the casing 15 and projects inwardly and to the inner end is attached the leg 34 of the yoke 35 within which is mounted the contact roller 36. This contact roller is adapted for riding engagement against the edge of the 35 flange 27 and when the semaphore is in inactive position, is normally seated in the recess 29 of the di-electric plate 28. A spring 37 has its intermediate portion convoluted about the shaft 17, while one end is attached to the casing 15 and its 40 opposite end attached to the shaft 17. Numeral 38 represents a flat spring attached at its lower end to the casing 15, while its upper end is split and disposed through a circumferential groove in the shaft 17 so as to steady the shaft 17 and to 45 prevent any longitudinal motion thereof. The end of the shaft 17 which projects beyond the dial face 16 is provided with a lever 39 whereby the shaft 17 can be actuated.

50 When the shaft 17 is actuated by the handle 39 and the roller 36 released from the notch 29 in the di-electric plate 28, the aforementioned spring 14 will lift the semaphore 6 upwardly until the roller 36 rides into the recess 30, whereupon the 55

phore will stop at the low active position, indicating a left turn.

If the roller 36 is tripped from this recess 30, the spring 14 will carry the semaphore 6 upwardly until the roller engages into the recess 31, at which point the semaphore will be in a horizontal position, such as is shown in Figure 1.

To indicate a right turn, the roller 36 is tripped from the recess 31 so that the spring 14 will carry the semaphore up further until the roller 36 engages into the recess 32.

As shown in Figure 1, numeral 40 represents a battery from which the lead wire 41 extends to the incandescent lamp 10 in the semaphore 6 and from this lamp extends the conductor 42 which connects to the flange 27 at the point 43, there always being a complete circuit for the lamp 10 when the roller 36 is off of the di-electric plate 28.

While the foregoing specification sets forth the invention in specific terms, it is to be understood that numerous changes in the shape, size and

materials may be resorted to without departing from the spirit and scope of the invention as claimed hereinafter.

Having described the invention, what is claimed as new is:—

In combination, a support, means for rotatably mounting a drum in said support, an operating cable attached to the periphery of said drum, said drum being provided with an inwardly disposed annulus, the inner edge of which is provided with spaced notches, a plate of insulation secured to the annulus adjacent one of the notches, said plate having a shallow notch therein registering with the aforementioned notch, a contact roller, means for resiliently mounting said roller on said support in a position to successively engage said notches as the drum is rotated, a signal circuit in which said annulus and roller are serially included, and means for manually rotating said drum.

JOHN FLORIAN WALDMAN.
